ABSTRACT OF THE DISCLOSURE

A clamping device for receiving punched Jacquard pattern cards comprising two parallel perforated clamping plates arranged on the changing frame in such a manner that the outer plate is resiliently mounted to provide a clamping action against the thrust of the reading pins so as to increase the life of the punched pattern cards.

This invention relates to clamping devices for Jacquard cards in automatic embroidering machines which comprise two parallel clamping plates, an inner one and an outer one, arranged on a changing frame and provided with holes for plate pins.

The Jacquard card, which is a punched card, is guided in the clamping device between the two clamping plates thereof and fed by means of a feed frame having feed pins engaging from outside into slots provided in the clamping plates. At the end of a feed stroke, the rows of holes in the card must be coincident with the holes in the clamping plates. In this manner the accuracy required for the sensing by the plate pins is obtained.

The partly punched Jacquard card will effect a preselection of the plates during the return movement of a changing frame. The plates which are in front of punched holes in the card remain in their initial positions, whereas the plates whose pins are not in front of punched holes will be pushed back, thereby to select the corresponding stitch values through plate levers and final differentials of the automatic control.

The Jacquard card will then be advanced by a feed stroke of the feed frame and the following stitch can be preselected and tripped.

In this arrangement the clamping plates must be sprung for fixing and retaining the Jacquard card so that the latter cannot fall down by gravity and thus trip wrong stitch values. Springing is also required to achieve a compensating effect with cards which are smudgy, pasted or differing in thickness.

In the prior art devices of this kind, the outer clamping plate is fixed and the inner clamping plate is sprung. Since the plate pins are abruptly and hard thrust through the Jacquard card into their preselecting positions, the card is subject to wear owing to the fact that holes are pierced by the plate pins. A further disadvantage consists in that in those cases where the Jacquard card is an endless strip of cardboard it cannot readily be removed from the clamping device for being exchanged. For this purpose holders must be detached and the clamping plates removed.

The object of the present invention is to eliminate the described disadvantages and to provide a clamping device for Jacquard cards which enables the thrust of the plate pins to be damped, simultaneously reducing the wear and substantially increasing the working speed.

This object is achieved according to the present invention by providing a clamping device for Jacquard cards in automatic embroidering machines, which comprises two parallel clamping plates arranged on a changing frame and having holes for plate pins, the inner clamping plate

2

facing the plate pins being fixed to the changing frame, spring means for pulling the outer clamping plate near the inner clamping plate, and guide pins for guiding the outer clamping plate.

5 In this arrangement, the plate pins now are brought in a smooth and damped manner through the cardboard of the Jacquard card into their preselecting positions and the number of cards run through per unit time is increased two to three times compared with the hitherto used arrangements.

10 It is possible to use different types of springs. For example, a spring wire may be arranged for pulling the outer clamping plate towards the inner clamping plate through the intermediary of the guide pins. Furthermore, 15 a compression spring arranged on each of the guide pins may be used for urging the outer clamping plate towards the inner clamping plate. It is also possible to arrange the outer clamping plate so that it will be pulled near the inner clamping plate by means of tension springs.

20 Finally, the invention can be realized by pivoting bail-like leaf springs to the inner clamping plate, in such a manner that the leaf springs can be snapped over the outer clamping plate for the purpose of pulling the outer clamping plate near the inner clamping plate.

25 Removal of the outer clamping plate is most simple. Several embodiments of the invention will now be described by way of example and with reference to the accompanying drawings, in which:

30 FIG. 1 is an exploded perspective view of a clamping device according to the invention, showing an arrangement using a spring wire for moving the outer clamping plate towards the inner clamping plate;

35 FIG. 2 is a perspective view of the two clamping plates of the device illustrated in FIG. 1, showing an arrangement using compression springs;

40 FIG. 3 is a view similar to FIG. 2, showing an arrangement using tension springs, and

45 FIG. 4 is a view similar to FIG. 2, showing an arrangement using leaf springs.

As shown in FIG. 1 of the drawings, a clamping device as proposed by the invention comprises an inner clamping plate 5 which can be fixed to the changing frames 1 and 2 by means of bolts 6 that can be passed through bores 17 in the latter, as well as an outer clamping plate 8 provided with guide pins 7. Between the changing frames 1 and 2 there are arranged the plates 3 carrying the plate pins 4.

50 Between the inner clamping plate 5 and the outer clamping plate 8 a Jacquard card (not shown) will be guided which is clamped therebetween in the operative position. The clamping plates 5 and 8 are provided with holes 9 through which the plate pins 4 can pass. The Jacquard card will be sensed by the plate pins 4 and the result will be transmitted to a known Jacquard machine controlling an automatic embroidering machine.

55 The inner clamping plate 5 is provided with sleeves 10 having longitudinal bores 29 for receiving the guide pins 7 of the outer clamping plate 8, thereby to enable this latter to be slidably displaced relative to the inner clamping plate 5. A spring wire 13 is provided with an eye 12 for being secured, for example by means of a bolt (not shown), to the inner clamping plate 5 which for this purpose is provided with a similar eye 11. In the assembled state of the device, the ends of the spring wire 13 are located in transverse grooves 14 of the guide pins 7. The spring provided by the spring wire 13 is rated so that it tends to pull the outer clamping plate 8 towards the inner clamping plate 5. By disengaging the ends of the spring wire 13 from the transverse grooves 14 the outer clamping plate 8 can be removed with the aid of a bail 15, without using a tool.

During the sensing operation, the outer clamping plate 8 will yield due to its springing, whereby the Jacquard card is preserved. The movement of the outer clamping plate 8 may be limited by stops. For the purpose of feeding the Jacquard card, feed pins 16 are provided which are adapted to engage into slots 18 in the clamping plates 5 and 8.

In the embodiment shown in FIG. 2, the guide pins 7 of the embodiment described with reference to FIGS. 1 are replaced by guide pins 19 carrying compression springs 20 which tend to urge the outer clamping plate 8 towards the inner clamping plate 5.

FIG. 3 shows an embodiment of the invention in which each end of the outer clamping plate 8 is provided with a lug 21 for securing one end of a tension spring 23 the other end of which is held by a pin 22 projecting from the sleeve 10 of the inner clamping plate 5. Guide pins 25 serve to guide the outer clamping plate 8 which has bores 30 in which the guide pins are slidably received. In the embodiment illustrated in FIG. 4, at each end of the inner clamping plate 5, a bail-like leaf spring 24 is pivoted to the sleeve 10 so as to be capable to be snapped over the outer clamping plate 8. When the leaf springs 24 are snapped over the outer clamping plate 8 they pull this latter towards the inner clamping plate 5. In this embodiment the outer clamping plate 8 is guided by means of guide pins 26 provided thereon and cooperating with corresponding bores 31 in the inner clamping plate 5. For locking the bail-like leaf spring 24 in its operative position it is provided with a hole 27 into which an end 28 of the pins 26 can be inserted.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein.

I claim:

1. A clamping device for Jacquard cards in automatic embroidering machines, comprising two parallel clamping plates arranged on a changing frame and having holes for plate pins, the inner clamping plate facing the plate pins being fixed to the changing frame, spring means for pulling the outer clamping plate near the inner clamping plate, and guide pins for guiding the outer clamping plate.
2. A clamping device as claimed in claim 1, wherein the spring means comprise a spring wire which is fixed to the inner clamping plate and transverse grooves are formed in the guide pins of the outer clamping plate, the spring wire engaging with its ends in the transverse grooves in the guide pins thereby to pull the outer clamping plate near the inner clamping plate through the intermediary of the guide pins.
3. A clamping device as claimed in claim 1, wherein the spring means comprise a compression spring which is arranged on each of the guide pins.
4. A clamping device as claimed in claim 1, wherein the spring means comprise a tension spring which is arranged to pull the outer clamping plate near the inner clamping plate.
5. A clamping device as claimed in claim 1, wherein the spring means comprise bail-like leaf springs which are pivoted to the inner clamping plate and can be snapped over the outer clamping plate for the purpose of pulling the outer clamping plate near the inner clamping plate.
